UNITED STATES PATENT OFFICE

168,704

BASE FOR TABLE LAMPS

Peter P. Ornstein, Los Angeles, Calif., assignor to Polynesian Sales Corporation, Chicago, Ill., a corporation of Illinois

Application August 8, 1952, Serial No. 20,951

Term of patent 7 years

(Cl. D48—20)

To all whom it may concern:

Be it known that I, Peter P. Ornstein, a citizen of Czechoslovakia, residing at Los Angeles, State of California, have invented a new, original, and ornamental Design for a Base for Table Lamps, of which the following is a specification, reference being had to the accompanying drawing, forming a part hereof.

Fig. 1 is a front perspective view of a base for table lamps, showing my new design; and

Fig. 2 is a rear perspective view thereof.

I claim:

The ornamental design for a base for table lamps, as shown.

PETER P. ORNSTEIN.
